UNITED STATES PATENT OFFICE

147,434

DESIGN FOR A BOOK END

Freda Diamond, New York, N. Y., assignor to Syracuse Ornamental Co. Inc., Syracuse, N. Y., a corporation of New York

Application March 23, 1946, Serial No. 127,872

Term of patent 3½ years

(Cl. D33—1)

To all whom it may concern:

Be it known that I, Freda Diamond, a citizen of the United States, residing in New York, in the county of New York and State of New York, have invented a new, original, and ornamental Design for a Book End, of which the following is a specification, reference being had to the accompanying drawing, forming a part thereof, wherein:

Fig. 1 is a front perspective view of a book end showing my new design; and

Fig. 2 is a side perspective view thereof.

I claim:

The ornamental design for a book end, substantially as shown.

FREDA DIAMOND.
